GRINDING MACHINE STEADY REST

Herbert A. Silven, Worcester, Mass., assignor to
 Norton Company, Worcester, Mass., a corpora-
 tion of Massachusetts

Application May 5, 1944, Serial No. 534,241

11 Claims. (Cl. 51—238)

This invention relates to grinding machines, and more particularly to a steadyrest for supporting and steadyng a work piece during a grinding operation.

One object of the invention is to provide a simple and thoroughly practical grinding machine steadyrest. Another object of the invention is to provide a hydraulically operated steadyrest which is compact in construction and simple in operation and action.

Another object of the invention is to provide a steadyrest of the two-bearing shoe type in which both of the steadyrest shoes are arranged to be moved to and from an operative position to facilitate indexing of the work supporting table.

Another object of the invention is to provide a steadyrest of the two-bearing shoe type in which both of the steadyrest shoes are pivotally mounted and arranged to be swung to an inoperative position so as to allow maximum clearance between the work and steadyrest parts when in an inoperative position.

A further object of the invention is to provide a rigidly supported bridge-type steadyrest which bridges the work supporting table and is arranged to be rigidly fixed to the base of the machine so as to support a work piece at a point opposite the grinding wheel. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings in which is shown one of various possible embodiments of the mechanical features of this invention,

Fig. 1 is a fragmentary cross sectional view through a crankshaft grinding machine showing the improved bridge-type steadyrest in elevation;

Fig. 2 is a fragmentary end elevation, on an enlarged scale, of the improved steadyrest, having parts broken away and shown in section to clarify the construction; and

Fig. 3 is a fragmentary cross sectional view, on an enlarged scale, taken approximately on the line 3—3 of Fig. 2.

A steadyrest has been illustrated in the drawings mounted on a grinding machine base 10. The base 10 supports a longitudinally reciprocable work supporting table 11 which is supported

on a V-way 12 and a flat way 13 formed on the base 10.

The improved steadyrest is particularly adapted for use on a crankshaft grinding machine for grinding crankpins such as shown, for example, in U. S. Patent No. 2,151,666 dated March 21, 1939. In a machine of this type, the steadyrest is preferably located in a fixed position relative to the base 10 opposite the operative face of a grinding wheel 14 so that the steadyrest shoes may support a crankpin 15 to be ground. The steadyrest shoes are arranged so that they may be moved to an inoperative position to provide a maximum clearance, when in an inoperative position, for the rotatably positioned work piece 15 mounted on the work table 11.

In order to provide a rigid support for the steadyrest shoes to steady a crankpin 15 against vibration during a grinding operation, a steadyrest frame 16 is provided in the form of a bridge-shaped member which straddles the work supporting table 11. The frame 16 is provided with an enlarged rectangularly shaped portion 17 which is rigidly fixed to the front of the machine base by a plurality of screws 18. The bridge-shaped frame 16 is provided with a rearwardly and downwardly extending arm 19 (Fig. 1) which is fixedly mounted by a plurality of screws 20 to a projection 21 formed on the rear of the machine base 10.

In the preferred form of this invention, in order adequately to support and steady work pieces such as the crankpins of an automobile crankshaft, a steadyrest of the two-bearing shoe type is provided in which the work is supported and steadied at a point diametrically opposite the line of contact between the grinding wheel 14 and the crankpin 15 and is also supported and steadied at a point below the work axis and adjacent to the line of contact between the wheel 14 and work piece 15.

As illustrated in the drawings, the steadyrest is provided with a work steadyng shoe 25 which is mounted on the upper end of an arm 26, the lower end of which is pivotally supported by a stud 27 on the steadyrest frame 16. The steadyrest shoe 25 is arranged to engage the work piece 15 at a point substantially diametrically opposite to the line of contact between the grinding wheel 14 and the work piece 15. The shoe 25 is held in an operative position by means of a pivotally mounted latch arm 28 which is pivotally supported by a stud 29. The forward end of the arm 28 is provided with a notch 30 which is arranged to engage the upper and left-hand surfaces of the

arm 26 to hold the shoe 25 in an operative position.

In order to facilitate adjustment of the shoe 25 to position the same at the start of a grinding operation and also to facilitate adjustment of the shoe 25 so that it remains in operative supporting engagement with the work 15 as the work is ground, the pivot stud 29 is preferably supported adjacent to the right-hand end of a horizontally adjustable slide 31 which is slidably mounted within the steadyrest frame 16. An adjusting screw 32 is screw threaded through a nut 33 supported by the steadyrest frame 16 and is provided at its right-hand end with a head 34 which engages a notch 35 formed in the left-hand end of the slide 31. An actuating knob 36 is adjustably supported on the outer end of the screw 32. By manipulation of the knob 36, the screw 32, the slide 31 and the latch arm 28 may be adjusted horizontally to position the work steadyrest shoe 25 in the desired relationship relative to the work piece 15.

A tension spring 37 is connected between a stud 38 mounted on the latch arm 28 and a stud 39 which is fixed relative to the steadyrest frame 16 to facilitate holding the arm in a latched position and also moving the arm 28 to an inoperative position.

The steadyrest shoe 25 is arranged to be swung into an inoperative position 25a, as illustrated in broken lines in Fig. 2. The latch arm 28 is also arranged to be swung to an inoperative position 28a (Fig. 2).

The steadyrest is also provided with a second work steadyrest shoe 40 which is arranged to engage the work piece 15 at a point below the work axis and adjacent to the line of contact between the grinding wheel 14 and the work piece 15. The shoe 40 is mounted on the right-hand end of a pivotally mounted supporting arm 41, the other end of which is pivotally supported by a stud 42. An actuating arm 43 is pivotally supported on the stud 27 and carries a rotatably mounted roller 44 on a stud 45 mounted adjacent to the upper end of the arm 43. When the actuating arm 43 is swung in a clockwise direction into the position illustrated in Fig. 2, the roller 44 engages the underside of the arm 41 and swings the arm 41 together with the steadyrest shoe 40 into an operative position. The actuating arm 43 is arranged to swing to an inoperative position 43a with the roller 44 assuming the position 44a, as shown in broken lines in Fig. 2. The steadyrest shoe 40 swings downwardly in a clockwise direction into position 40a with its supporting arm assuming the position 41a, as shown in broken lines in Fig. 2.

The actuating arm 43 is preferably hydraulically actuated so that it may be readily swung to and from an operative position. A hydraulically operated cylinder 46 is fixedly supported relative to the steadyrest frame 16 and contains a slidably mounted piston 47 which is connected to one end of a piston rod 48. The other end of the piston rod 48 is provided with a fixed collar 49 which is connected by means of a stud 50 with the left-hand end of a connecting rod 51. The other end of the connecting rod 51 is connected by a stud 52 which is supported on the actuating arm 43. When it is desired to move the actuating arm 43 to an inoperative position, fluid under pressure is admitted through a pipe 53 into a cylinder chamber 54 formed at the right-hand end of the cylinder 46 to cause the piston 47 to move toward the left (Fig. 2). During this movement of the

piston 47, fluid within a cylinder chamber 55 exhausts through a pipe 56. When the piston 47 moves toward the left, a corresponding movement is imparted through the connecting rod 51 to swing the actuating arm 43 in a counterclockwise direction into position 43a. When it is desired to move the actuating arm 43 to an operative position, fluid under pressure is admitted through the pipe 56 into the cylinder chamber 55 to move the piston 47 toward the right, so as to swing the actuating arm 43 in a clockwise direction into the full line position shown in Fig. 2.

In order to facilitate adjustment of the steadyrest shoe 40 in setting up the steadyrest and also in maintaining the shoe 40 in operative supporting and steadyng engagement with the work piece 15 as it is ground, the stud 42 is preferably adjustably mounted so that the arm 41 may be rocked on the roller 44 as a fulcrum to raise and lower the shoe 40 as desired. The stud 42 is preferably supported on the upper end of a slidably mounted member 60. The member 60 is provided at its lower end with a roller 61 supported thereon by a stud 62. The roller 61 is positioned to engage a cam face 63 which is formed on a horizontally adjustable slide 64. A compression spring 65 within the slide member 60 normally tends to urge the slide 60 in an upward direction so that the roller 61 is maintained in operative engagement with the cam face 63. The slide 64 is preferably adjusted by means of an adjusting screw 66 which is screw threaded into a nut 66 fixedly supported in the frame 16 of the steadyrest. A head 67 is formed on the right-hand end of the screw 66 and is arranged to engage a notch 68 formed in the left-hand end of the slide 64. An actuating knob 69 is adjustably mounted on the outer end of the screw 66. It will be readily apparent from the foregoing disclosure that by manipulation of the knob 69, the screw 66 and slide 64 may be adjusted to impart a swinging adjustment to the arm 41 about the roller 44 as a fulcrum to adjust the steadyrest shoe 40 relative to the work piece 15.

It is desirable to provide connections between the actuating arm 43 and the arm 26 so that both of the steadyrest shoes 25 and 40 may be swung to and from operative positions by movement of the actuating arm 43. The actuating arm 43 is provided with a stud 70 which rides within an arcuate shaped slot 71 formed in the arm 26. A compression spring 72 is contained within an aperture 73 formed in the arm 26 and is arranged to be engaged by the stud 70 when the actuating arm 43 is swung in a clockwise direction to move the shoe 40 into an operative position so that at the same time the stud 70 operating through the compression spring 72 will swing the arm 26 into an operative position, as shown in Fig. 2.

In order that the shoe 25 may be readily moved to an inoperative position in timed relation with the movement of the actuating arm 43, a suitable latch releasing mechanism is provided comprising a slidably mounted plunger 75 which is slidably mounted within the arm 26. The plunger 75 is normally held in a downward position by means of a compression spring 76 which is interposed between a shoulder 77 formed on the arm 26 and a shoulder 78 formed on the plunger 75. The lower end of the slide 75 is provided with a cam face 79 which is arranged in the path of the stud 70.

When it is desired to move the steadyrest shoes 25 and 40 to an inoperative position, fluid under pressure is admitted, as above described, into the

cylinder chamber 54 to cause the actuating arm 43 to move in a counterclockwise direction, which movement shifts the roller 44 also in a counterclockwise direction to allow the steadyrest shoe 40 to swing downwardly in a clockwise direction out of engagement with the work piece 15. The stud 70 engages the cam face 79 and moves the plunger 75 in an upward direction so that its end portion assumes the position 75b (Fig. 2), which movement lifts the latch arm 23. Continued movement of the actuating arm 43 in a counterclockwise direction through the stud 70 will swing the arm 23 together with the work steadyrest shoe 25 in a counterclockwise direction into positions 25a and 26a so that both of the steadyrest shoes 25 and 40 are in inoperative positions, allowing a maximum clearance between the work and the steadyrest parts so that the work table supporting a massive crankshaft may be readily traversed longitudinally to position the next crankpin in an operative position for a grinding operation. During the swinging movement of the arm 26 to an inoperative position, the released tension of the spring 37 serves to swing the latch arm 23 into position 26a so that it also is in an inoperative position remote from the work piece.

The operation of this steadyrest will be readily apparent from the foregoing disclosure, assuming the steadyrest shoes 40 and 25 to be in an inoperative position, such as shown in broken lines in Fig. 2, that is, the shoes being in positions 25a and 40a. When it is desired to move the shoes into an operative position, fluid under pressure is admitted through the pipe 56 into the cylinder chamber 55 to move the piston 47 toward the right into the full line position illustrated in Fig. 2. This movement of the piston 47 serves through the piston rod 51 and the stud 52 to swing the actuating arm 43 in a clockwise direction, which movement, through the roller 44, 40 swings the arm 41 and the steadyrest shoe 40 in a counterclockwise direction into the operative position illustrated in Fig. 2. The movement of the actuating arm 43, through the stud 70 and the compression spring 72, serves to swing the arm 26 also in a clockwise direction into the operative full line position shown in Fig. 2 with the steadyrest shoe 25 in an operative position relative to the work piece 15. During this swinging movement of the arm 26, the latch arm is also swung upwardly in a counterclockwise direction by movement of the arm 26 and shoe 25 against the tension of the spring 37 until the notch 38 may drop into a latched position to latch and hold the arm 26 together with the shoe 25 in an operative position. After the shoes 25 and 40 are in operative positions, they may be adjusted precisely to initially set up the work rest by manipulation of the actuating knobs 36 and 69, and the steadyrest shoes may be maintained in the desired supporting and steadyng engagement with the work piece.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. A grinding machine steadyrest having a

frame, a work steadyng shoe pivotally mounted on said frame which is arranged to engage and steady the work at a point opposite the grinding wheel, a second work steadyng shoe independently and pivotally mounted on said frame which is arranged to engage and steady the work at a point below the work axis and adjacent to the line of contact between the grinding wheel and work, said shoes normally being in an inoperative position, and a movably mounted actuator arm which is arranged simultaneously to move both of said shoes into an operative position.

2. A grinding machine steadyrest having a frame, a work steadyng shoe to engage and steady the work at a point opposite the grinding wheel, a movable support on said frame to support said shoe, a second work steadyng shoe to engage and steady the work at a point below the work axis and adjacent to the line of contact between the grinding wheel and work, an independent movable support on said frame to support said second shoe, said shoes normally being swung to an inoperative position, and a pivotally mounted actuator arm on said frame which is operatively connected simultaneously to move both of said movable supports and shoes to an operative position.

3. A grinding machine steadyrest having a frame, a work steadyng shoe arranged to engage and steady the work at a point opposite the grinding wheel, a pivotally mounted arm on said frame to support said shoe, a second work steadyng shoe to engage and steady the work at a point below the work axis and adjacent to the line of contact between the grinding wheel and work, a second independent pivotally mounted arm on said frame to support said second shoe, said shoes normally being maintained in an inoperative position remote from the work piece, a pivotally mounted actuator arm on said frame, and means including a piston and cylinder which are operatively connected to swing said actuator arm simultaneously to move both of said arms and shoes to an operative position.

4. A grinding machine steadyrest having a frame, a pivotally mounted work steadyng shoe arranged to engage and steady the work at a point opposite the grinding wheel, a latch to hold said shoe in an operative position, a second pivotally mounted work steadyng shoe to engage and steady the work at a point below the work axis and adjacent to the line of contact between the grinding wheel and work, and a pivotally mounted actuator arm which is arranged to move both of said shoes to an operative position, said actuator arm serving to hold said second shoe in an operative position, and said shoes being arranged to swing to an inoperative position when the actuator arm is moved to an inoperative position.

5. A grinding machine steadyrest having a frame, a pivotally mounted work steadyng shoe to engage the work at a point opposite the grinding wheel, a latch to hold said shoe in an operative position, a second pivotally mounted work steadyng shoe to engage and steady the work at a point below the work axis and adjacent to the line of contact between the grinding wheel and work, a pivotally mounted actuator arm which is arranged to move both of said shoes to an operative position, and a slidably-mounted cam-actuated latch-releasing plunger which is actuated by movement of said actuator arm to an inoperative position to release said latch to facilitate movement of the first steadyrest shoe to an inoperative position.

6. A grinding machine steadyrest having a frame, a pivotally mounted work steadyng shoe arranged to engage and steady the work at a point opposite the grinding wheel, a pivotally mounted latch arm to hold said shoe in an operative position, a second pivotally mounted work steadyng shoe to engage and steady the work at a point below the work axis and adjacent to the line of contact between the grinding wheel and work, a pivotally mounted actuator arm which is arranged to move both of said shoes to an inoperative position, a pivotally mounted latch arm to hold said first shoe in an operative position, a slidably-mounted cam-actuated latch-releasing plunger, and a stud on said actuator arm which is arranged to engage said cam and actuate said releasing plunger during movement of the actuator arm toward an inoperative position to facilitate movement of the first steadyrest shoe to an inoperative position.

7. A grinding machine steadyrest having a frame, a pivotally mounted work steadyng shoe to engage and steady the work at a point opposite the grinding wheel, a latch to hold said shoe in an operative position, a second pivotally mounted work steadyng shoe to engage and steady the work at a point below the work axis and adjacent to the line of contact between the grinding wheel and work, a pivotally mounted actuator arm which is arranged to move both of said shoes to an operative position, and manually operable means to adjust the position of said latch relative to said frame so as to adjust the first steadyrest shoe relative to the work piece.

8. A grinding machine steadyrest having a frame, a pivotally mounted work steadyng shoe to engage and steady the work at a point opposite the grinding wheel, a pivotally mounted latch

arm to hold said shoe in an operative position, a second pivotally mounted work steadyng shoe to engage and steady the work at a point below the work axis and adjacent to the line of contact between the grinding wheel and work, a pivotally mounted actuator arm to move both of said shoes to an operative position, an adjustable slide to support said latch arm, and manually operable means to adjust the position of said slide so as to adjust the first steadyrest shoe relative to the work piece.

9. In a grinding machine steadyrest as claimed in claim 8, the combination with the parts and features therein specified, of an adjustable slide to support the second pivotally mounted shoe, and manually operable means to adjust the position of said slide so as to adjust the second steadyrest shoe relative to the work piece.

10. In a grinding machine steadyrest as claimed in claim 8, the combination with the parts and features therein specified, of an adjustable slide to support the second pivotally mounted shoe, and a manually adjustable cam to move said slide so as to adjust the position of the second steadyrest shoe relative to the work piece.

11. In a grinding machine steadyrest as claimed in claim 8, the combination with the parts and features therein specified, of a vertically adjustable slide to support the second pivotally mounted shoe, a roller mounted adjacent to the lower end of said slide, a horizontally adjustable slide having a cam face which is arranged operatively to engage said roller, and means including a manually adjustable nut and screw mechanism to actuate said horizontally movable slide to facilitate adjustment of the second steadyrest shoe relative to the work piece.

HERBERT A. SILVEN.
